PLIERS

Robert Myers, San Francisco, Calif., assignor to
 M. J. Lampert & Sons, Inc., New York, N. Y., a
 corporation of New York

Application September 8, 1936, Serial No. 99,739

2 Claims. (Cl. 81—15)

This invention relates to pliers or tools which may be used by jewelers or the like, its principal object being to provide a plier for use in opening up the short links of the chains of bracelets, such as are now much in vogue, such chains including main ornamental links which are connected together by means of shorter links, each of which is in the nature of a small closed loop of metal made from short strips, the ends of which 10 are usually bent around in abutting relation. It is frequently necessary for a workman to repair such bracelet chains or the like or to either lengthen or shorten the chain, in which cases the workman by means of the improved plier may 15 sufficiently open up one of the short links, of which the joint is at one side, with ease and effectiveness with a view to disconnecting the adjacent main links which are connected by such opened up link and then proceed to do what is necessary 20 to the chain or bracelet.

With these ends in view the invention provides a tool or plier which includes connected, opposed, movable jaws having terminals which are transversely of wedge shape at opposing points, the 25 sides of the wedge shaped portions diverging from the adjacent opposing edges of the terminals, and such features are desirably embodied in a plier with a pair of pivotally connected jaws.

These being among the objects and features of 30 the present invention, the same consists of certain details of construction to be hereinafter described and then claimed with reference to the accompanying drawing illustrating a preferred embodiment of the invention and wherein

Fig. 1 is a side view of the improved plier slightly enlarged and with the jaws somewhat opened;

Fig. 2 is an enlarged side view of the jaws broken away from the handles of the plier, the jaws being shown as closed;

Fig. 3 is a transverse section on line 3—3 of Fig. 2, the jaws being closed and viewed in the direction of the arrow;

Fig. 4 is a view of one of the jaws broken away and viewed towards its inner edge;

Fig. 5 is a perspective view of one of the jaws broken away;

Fig. 6 is a sectional elevation on line 6—6, Fig. 7, showing the pliers entering a link which is to be opened up for removal; and

Fig. 7 is a side elevation on line 7—7, Fig. 6, showing the jaws of the plier engaged with the slotted ends of a link to open up the same.

The invention is preferably embodied in a plier such as shown in Fig. 1, the same including a 55 pair of handles 10, 11 and a pair of jaws 12, 13

which are carried respectively by the handles 11, 10 and connected together by a pivot 14. The jaws 12, 13 of the plier oppose each other and the details of the features embodied in the invention are illustrated on an enlarged scale in Figs. 2, 3, 4 and 5. It is preferable that the plier include only two operating members connected together by a single pivot, such members being formed of hard metal, preferably steel. The plier is preferably of such size and shape that it may be conveniently 10 grasped in one hand of a workman, which may be either his right or his left hand, as the improved features thereof are duplicated in the jaws 12, 13.

Referring to Figs. 2 to 5 inclusive each jaw 12, 15 13 is provided with a terminal portion 15, which terminal is wedge shaped transversely, so that the jaws are provided with wedge shaped portions 16 preferably formed by providing the terminal portions 15 with recesses 17 at opposite 20 sides of each terminal portion, the bottoms or closed walls of the recesses converging so as to provide each wedge portion 16 with more or less of a knife edge at 18. The edges 18 preferably diverge from the bodies of the jaws 12, 13 at the 25 inner edges of the pair, as shown in Fig. 2.

By providing the opposed recesses 16 in each jaw there is formed at the end surfaces of the terminal portions tapering or wedge shaped shoulders 19, so that the tips of the jaws are similarly tapered in the same direction as the wedge portions 16. The shoulders 19 at each side of each terminal portion are extended inwardly sufficiently to overhang or extend slightly inwardly of the diverging edges of the wedge shaped portions, 30 thereby providing for each jaw an opposing seat or nose 20. When the jaws are closed together as shown in Fig. 2 it will be seen that an eye is formed between the terminal portions of the jaws which is of such width at its greater dimension 35 as to take in the cross dimension of the smallest link of a chain which is to be opened up.

Referring more particularly to Figs. 6 and 7, the operation and use of the improved tool or plier will be more readily understood. A chain 45 to which the invention is adapted for use comprises short links 21 connecting longer links 22, and only a few of these links are shown to enable an understanding of the invention. The links 21 are composed of flexible or bendable 50 metal and connect the longer links, and the ends of the strip which forms the short link are butted together to provide a closed loop. When it is desired to open up a short link, such as 21, the terminal portions 15 of the plier are opened suf- 55

ficiently so that the noses or teats 20 may be engaged in the eye of the loop or link 21, so as to dispose the edges 18 of the wedge portions 16 in opposed relation at the joint 23 of the link 21.

5 Then by pressing the jaws firmly together the wedge portions 16 will enter the joint 23 and they will act to spread apart the ends of the link at that joint to such extent that the link 21 may be disconnected from the adjacent main links

10 22, for enabling the repair, the lengthening or the shortening of the bracelet chain. It will be seen that when the jaws are fully closed together the noses or teats 20 will be in abutting relation for the smallest cross-dimension of openable link,

15 but that for wider links they will simply be in opposition, but in either case the wedge portions will spread the link open. A further opening up of the link may be accomplished when the tool or plier is pulled out from the link inasmuch as

20 the shoulders 19 have the function of further opening the link if the jaws have not been moved apart any further than is merely necessary to spread the ends of the link apart by the action of the wedge portions. It will be seen that the

25 convergence of the wedge edges 18 tends to press the link towards the shoulders 19 and teats 20.

It will be obvious to those skilled in the art

that the invention as shown and described is susceptible to more or less modification without departing from the scope of the appended claims.

What I claim as new is,

1. A tool of the character described, including 5 a pair of pivotally connected jaws having terminals each of which is recessed at opposite sides, at opposing points of the terminals, the bottoms of the recesses diverging from the adjacent opposing edges of the terminals to provide wedge- 10 shaped portions, and the terminals having transverse, correspondingly wedge-shaped, shoulders defined by the recesses and located at the tips of the terminals.

2. A tool of the character described, including 15 a pair of pivotally connected jaws having terminals each of which is recessed at opposite sides, at opposing points of the terminals, the bottoms of the recesses diverging from the adjacent opposing edges of the terminals to provide wedge- 20 shaped portions, and the terminals having transverse, correspondingly wedge-shaped, shoulders defined by the recesses and located at the tips of the terminals, the opposed edges of the wedge-shaped portions diverging toward the shoulders 25 to provide an eye when the jaws are fully closed.

ROBERT MYERS.
